(57) **CLAIM**

The ornamental design for a label printer, as shown and described.

DESCRIPTION

FIG. 1 is a perspective view of a label printer showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1.

2.

FIG. 11 is an enlarged detail view of area 11 shown in FIG. 3; and,

FIG. 12 is an enlarged detail view of area 12 shown in FIG. 6.

The long-dash broken lines define the bounds of the enlarged views and form no part of the claimed design.

The short-dash broken lines in the drawings depict portions of the label printer that form no part of the claimed design.

1 Claim, 12 Drawing Sheets
